[57] **ABSTRACT**

A contact system for a high-voltage circuit breaker of the compressed-gas type or the like defines a gap across which an arc is drawn when the breaker is switched to the open position. The contact system includes at least one hollow, nozzle-shaped contact piece which defines one end of the gap when the breaker is switched to the open position. The contact piece includes an electrically conductive tubular member made of cold work-hardened copper. A nozzle-shaped body made of arc-resistant graphite is cold press-fitted into the tubular member at an end portion thereof so as to be held in surrounding engagement thereby in a friction-tight manner.

CONTACT SYSTEM FOR A HIGH-VOLTAGE CIRCUIT BREAKER

BACKGROUND OF THE INVENTION

Deutsche Auslegungsschrift No. 1,154,548 discloses an electric circuit breaker wherein an electro-negative, fluorine containing gas such as sulphur hexafluoride or the like is utilized as the quenching and insulating medium. The circuit breaker includes two contact pieces which are movable relative to each other and across which an arc is drawn when the breaker is opened. The contact pieces are made of carbon, preferably graphite, in order to keep the destruction of the contact and the formation of decomposition products low during the time that the arc is effective. The graphite contact pieces are solid and are inserted into cup-shaped electrodes. The walls of the cup-shaped electrodes engage at least partially with undercuts on the periphery of the contact pieces to achieve a secure mechanical and electrical connection.

In high-voltage power circuit breakers, and in particular, in compressed-gas circuit breakers, it is advantageous to make the contact pieces hollow and suitable for exhausting the arc gases which are produced during the opening operation of the breaker. The hollow contact pieces have end faces whereat they carry the arcing electrodes. As disclosed in United States Patent application, Ser. No. 348,288, filed Apr. 5, 1973, these arcing electrodes can have an annular configuration and can be provided with a U-shaped profile. A supporting body is arranged between the legs of the U-shaped profile. In this embodiment, the graphite electrode is held in a friction-tight manner so as to be secured against breakage and to be mechanically stable.

United States Patent application, Ser. No. 344,045 filed Mar. 22, 1973, discloses how an annular graphite electrode is held by an annular electrically conductive member in a friction-tight manner. The annular member is in turn joined tightly to the corresponding contact piece and the graphite member is configured to have a nozzle-like shape for conducting away the switching gases. The intermediate member which holds the electrode in place in this arrangement can be chosen with respect to the currents and the material composition in such a manner that favorable coefficients of expansion relative to the graphite electrode result. The graphite electrode must withstand high thermal stress because of the arc.

The arrangements disclosed in the two above-mentioned Patent Applications require press fits in which the graphite nozzle as the inserted part is cooled below the surrounding metal annular member while the annular member is brought to a high temperature.

It is desirable to make the contact piece supporting the graphite electrode of a high electrically conductive material, particularly copper, so that high rated currents can be transmitted without appreciable temperature rise. The use of copper tubing as the holder for the graphite electrodes, however, causes problems because, with the interference required for the friction fit, it is possible that the strength of the copper can be exceeded. A shrink joint can therefore produce a tear.

SUMMARY OF THE INVENTION

It is an object of the invention to join the graphite electrode to the copper member in a contact system for

high-voltage power circuit breakers. Subsidiary to this object, it is an object of the invention to provide a friction-tight joint between the graphite electrode and copper member which overcomes the disadvantages delineated above.

A contact system according to the invention is utilized in a high-voltage circuit breaker of the compressed-gas type or the like. The contact system defines a gap which is blasted with gas to quench an arc drawn thereacross when the breaker is switched to the open position. The contact system includes at least one hollow, nozzle-shaped contact piece defining one end of the gap when the breaker is switched to the open position. According to a feature of the invention, the contact piece includes an electrically conductive tubular member made of cold work-hardened copper and a nozzle-shaped body made of arc-resistant graphite cold press-fitted into the work-hardened tubular member at the end portion thereof so as to be held in surrounding engagement thereby in a friction-tight manner.

The nozzle-shaped body consisting of graphite is thus pressed into the tube in cold condition and is embraced by the latter so as to form a friction fit therewith. The cold work-hardening of the copper tube causes the strength properties thereof to be substantially increased; these properties are maintained below the recrystallization temperature of the copper material used in each case, for instance, +150°C. The copper tube can consequently withstand the forces safely, which are required for a friction fit. With the invention, a joint is achieved which securely joins the copper and graphite members with each other.

In one preferred embodiment the peripheral surface intended for the friction fit with the tube is formed by a cylindrical recess of the nozzle-shaped body which engages with a matching internal cylindrical recess of the tube. The radial dimension of the internal recess of the tube can be about one-half of the wall thickness of the tube.

An amount of interference of the outer surface of the nozzle-shaped body relative to the tube recess is preferably provided such that in a temperature range between -40° and +120°C, the pressure stresses of the material of the nozzle-shaped body and of the tube material do not exceed the permissible value at any point of the engagement area. In order to prevent chipping or cracking of the nozzle-shaped body, it is advantageously stressed only in compression in the engagement area.

Although the invention is illustrated and described herein as a contact system for a high-voltage circuit breaker, it is nevertheless not intended to be limited to the details shown, since various modifications may be made therein within the scope and the range of the claims. The invention, however, together with additional objects and advantages will be best understood from the following description and in connection with the accompanying drawings.

BRIEF DESCRIPTION OF THE DRAWING

The drawing illustrates the contact system according to the invention. The contact system is shown disposed in the switching chamber of an electric high-voltage power circuit breaker of the compressed-gas type. The top half of the drawing above the center line shows the movable bridging member in a position corresponding to the closed position of the breaker, and in the lower

half, the bridging member is shown for the open position of the breaker.

DESCRIPTION OF THE PREFERRED EMBODIMENTS OF THE INVENTION

The circuit breaker has a switching chamber 2 consisting of porcelain, for example. The interior 1 of the chamber 2 is filled with sulfur hexafluoride as the quenching and insulating medium. The switching chamber 2 is of tubular shape and includes two centrally disposed stationary contact pieces 3, 4; these contact pieces are mutually adjacent so as to define a gap therebetween and are of identical configuration. The contact pieces 3, 4 each include an electrically conducting tube 5, 6. Each of the tubes, 5, 6 has an end portion whereat a nozzle-shaped body 7, 8 made of graphite is carried, the graphite being an arc-resistant material. The two tubes 5, 6 are made of copper and are bridged in an electrically conducting manner by a bridging contact member 12 when the breaker is in the closed position as shown above the longitudinal center line.

Through a movement of the bridging contact member 12 in the direction of the arrow 13, the bridging contact member 12 arrives in the position shown below the center line which corresponds to the open position of the breaker. When the member 12 moves to the open position, an arc is drawn between the graphite nozzle-shaped bodies 7 and 8. A jet of gas originating in the interior 1 of the switching chamber 2 drives the arc into the interior of the hollow, nozzle-shaped contact pieces 3 and 4 until it is extinguished at the zero crossing of the alternating current.

The tubes 5 and 6 of the contact pieces consist of cold work-hardened copper and have each, in the area of the end portion, a recess in the form of a cylindrical counterbore 9, the radial dimension of which is about one-half of the wall thickness a of the tubes 3, 4. The nozzle-shaped bodies 7, 8 each have a cylindrical open recess 11 at their outer surface 10 which establishes a friction fit with the corresponding tube 5 or 6. The nozzle-shaped bodies 7, 8 consisting of graphite are cold pressed into the counterbore 9 of the tubes 5 and 6 so as to leave part of the nozzle-shaped bodies 7, 8 protruding. During the pressing operation, grooves are produced in the graphite body at the cylindrical surface 11 through scoring action. The material from these grooves is present, for instance, in the form of powder and can serve as a lubricant during the pressing operation.

The configuration of the tubes 5, 6 with a counterbore 9 relieves the nozzle-shaped bodies of load in the region of the unengaged end of the body where a fracture could occur; this configuration also ensures a greater area over which pressure is applied at the engaged end of the nozzle-shaped body because there, the recessed region of the tube is aided by the adjacent bounding portion of the tube.

For the surface portion of the nozzle-shaped body 10, 11 such an amount of interference relative to the tube counterbore 9 is preferably chosen so that in a temperature range between -40° and $+120^{\circ}\text{C}$, the permissible tensile stresses for the tube material (copper) and the permissible compression stresses for the material of the nozzle-shaped body (graphite) are not exceeded at any point of the engagement area wherewith the area pres-

sure in the engagement area does not fall below the required value.

In a preferred embodiment, the following data are obtained:

5

Tube, tensile stress	25	kp/mm ²
Nozzle-shaped body, compression stress	4	kp/mm ²
Area pressure	0.4-1.2	kp/mm ²
Interference	approx.	2.5%

10

With the invention, it is possible to configure the part of the contact piece holding the nozzle-shaped graphite body of a material favorable for carrying rated current of the power circuit breaker; such a material is copper and the required strength properties are achieved by cold work-hardening. This ensures that the nozzle-shaped body is subjected in the engagement area to a pressure that assures a friction fit without the copper flowing in the engagement area. Making the joint requires no particular heat treatment and no subsequent finishing of the joined parts is needed.

Although the contact system is described in the context of high-voltage power circuit breakers and particularly compressed-gas circuit breakers, it can be applied to other high-voltage equipment provided with a gaseous insulating medium. Thus, it is, for example, possible to equip load disconnect switches with the contact system according to the invention. It is also possible to equip overvoltage arresters with the contact system of the invention at the gas-filled spark gaps thereof.

30 What is claimed is:

1. A contact system for a high-voltage circuit breaker of the compressed-gas type or the like, the contact system defining a gap which is blasted with the gas to quench an arc drawn thereacross when the breaker is switched to the open position, the contact system comprising at least one hollow, nozzle-shaped contact piece defining one end of the gap when the breaker is switched to the open position, said contact piece including an electrically conductive tubular member made of cold work-hardened copper, said tubular member having end portion, a nozzle-shaped body made of arc-resistant graphite, said nozzle-shaped body being cold press-fitted into said tubular member at said end portion thereof so as to be held in surrounding engagement thereby in a friction-tight manner.

2. The contact system of claim 1, said tubular member having a counterbore formed in the inner surface thereof at said end-portion, and said nozzle-shaped body having an open cylindrical recess adapted to said counterbore and formed in its outer surface for engaging said tubular member in a friction-tight manner at said counterbore.

3. The contact system of claim 2, said counterbore being a recess in the inner surface of said end-portion, said recess having a dimension measured in radial direction equal to approximately one-half the thickness of said tubular member beyond said end portion.

4. The contact system of claim 2, said nozzle-shaped body being dimensioned to have an amount of oversize of said cylindrical surface relative to said counterbore so as to cause the compressive stress developed in the material of said nozzle-shaped body and the tensile stress developed in said tubular member to remain within the respective allowable values therefor at all points of the engagement area of said nozzle-shaped body and said tubular member in the temperature range of -40°C to $+120^{\circ}\text{C}$.
